UNITED STATES PATENT OFFICE.

HENRY SKREMKA, OF NEW YORK, N. Y.

STAGE-COSTUME APPLIANCE.

1,398,158.

Specification of Letters Patent.

Patented Nov. 22, 1921.

Application filed July 30, 1921. Serial No. 488,673.

To all whom it may concern:

Be it known that I, HENRY SKREMKA, a citizen of the United States, and a resident of the city of New York, borough of Manhattan, in the county of New York and State of New York, have invented a new and Improved Stage-Costume Appliance, of which the following is a full, clear, and exact description.

10 My invention relates to a stage costume appliance and aims to provide a device of this character by means of which, certain novel and spectacular effects may be achieved.

15 It is an object of my invention to provide a device of the character stated, which shall be relatively simple in construction and by means of which, the costume worn by a person may be caused to be manipulated and 20 moved with respect to the body of the person to produce an illusion which shall be both novel and pleasing to the eye.

A still further object of this invention is the provision of an appliance, the parts of 25 which, will be extremely simple in construction, and which shall provide means tending to support the device in such a manner that no discomfort will result.

Further objects of this invention will appear in the annexed specification, taken in 30 connection with the drawings, which latter present one practical embodiment of the same, and in which;

Figure 1 is an elevational view of a costume applied to the figure of a wearer and supported by means of my improved appliance;

Fig. 2 is a plan view of the said appliance;

Fig. 3 is a perspective view of the same 40 and illustrating the apparatus in applied position;

Fig. 4 is a side elevation of the said appliance;

Fig. 5 is a plan view of the same with 45 the parts illustrated in Fig. 2 removed therefrom; and

Fig. 6 is a transverse sectional view taken on the line 6—6 and in the direction of the arrows indicated in Fig. 5.

50 Referring now more particularly to Figs. 3 to 6, it will be noted that in the embodiment illustrated that the appliance includes a split ring 10, about which an annular band 11 is concentrically disposed, the latter being 55 retained in applied position by means of

suitable guide elements 12, associated with the former.

With a view of supporting the device on the body of a wearer, a belt 13 is utilized and straps 14 extend between this belt and rods 15, which latter are secured to the ring 10, it being noted in this connection that cables 16 may be provided for use as handles, so that the entire device may be supported while the belt 13 is being adjusted 65 to conform to the body.

With a view of affording suitable rigidity, it will be noted that a backing plate 17 is conveniently affixed to the ring 10 and this backing plate may carry pads, 18 which bear 70 against the torso, so that the entire appliance by means of these parts, together with the belt 13 possesses a sufficient amount of rigidity.

To now provide means serving to move 75 the band 11 with respect to the relatively fixed portions of the appliance, it will be seen that the inner face of the band 11 is formed with teeth 19 and a motor 20, which in the embodiment illustrated, is spring 80 driven, is utilized to effect the rotation of a gear 21 meshing with the teeth 19. Thus, when the motor rotates the gear 21, the band 11 will rotate with respect to the ring 10. Also to furnish a suitable locking mechanism to retain the parts normally fixed with respect to each other, I may conveniently employ a spring pressed dog 22, which is mounted upon the ring 10 and normally 85 engages the teeth 19, thus preventing movement of the band with respect to the ring. To control the operation of this member, however, a Bowden wire 23 is connected to the same and this element terminates in a hand grip portion 24, which as in Fig. 1, 90 95 may be concealed by suitable artistic trimming 25.

Thus, at the will of the wearer, the appliance may be caused to operate by simply actuating the hand grip 24, which will unlock the parts, although a release of the hand grip will immediately cause a cessation of this operation. The mounting for the dress 25' is provided by means of utilizing the shield, best illustrated in Figs. 2 and 6. 100 105

Referring to the former figure, it will be noted that this element includes a body portion 26, to which are secured fastening elements 27 of a nature permitting of the attachment of the dress 25' thereto. Arcuate 110

panels 28 are hingedly associated with the body 26 so that after an operator has donned the appliance, the panels may be swung to a position at which they will properly embrace the waist and screws may be introduced through openings 29 so as to engage screw threaded lugs 30 affixed to the band 11 and thus the entire shield is supported by the band and will consequently move with the 10 same.

Thus it will be obvious that all the objects set forth in the preamble of this specification have been accomplished in that a device is provided which will produce an extremely 15 artistic and pleasing effect, this device being absolutely within control of the wearer.

Also obviously numerous modifications of structure might readily be resorted to without in the least departing from the scope of 20 my claims, which are—

1. A stage costume appliance, including means adapted to encircle the body of a wearer, means connected therewith for supporting the costume, and further means for 25 causing a rotary motion of said supporting means with respect to said first named means.

2. A stage costume appliance, including a ring adapted to encircle the body of a wearer, 30 a band movably carried by said ring, and means associated with one of said elements for causing a movement thereof with respect to the other.

3. A stage costume appliance, including a ring adapted to encircle the body of a wearer, 35 a band movably carried by said ring, a motor carried by said ring, and means connecting said motor with said band.

4. A stage costume appliance, including a ring adapted to encircle the body of a wearer, 40 a band movably carried by said ring, means for moving said band with respect to said ring, and means connected to said ring for attaching the same to the body of a wearer.

5. A stage costume appliance, including a ring adapted to encircle the body of a wearer, 45 a band movably carried by said ring, means for positively moving said band with respect to said ring, and a shield carried by said band.

6. A stage costume appliance, including a ring adapted to encircle the body of a wearer, a band movably carried by said ring, a series 55 of teeth formed in the inner face of said band, a gear wheel engaging said teeth, and means for rotating said gear wheel.

7. A stage costume appliance, including a ring adapted to encircle the body of a wearer, a band movably carried by said ring, a series 60 of teeth formed in the inner face of said band, a gear wheel engaging said teeth,

means for rotating said gear wheel, and a belt attached to said ring.

8. A stage costume appliance, including a ring, a band movably carried by said ring, a series of teeth formed in the inner face of said band, a gear wheel engaging said teeth, means for rotating said gear wheel, a belt connected to said ring and adapted to encircle the body of a wearer, and a backing plate 70 also attached to said ring.

9. A stage costume appliance, including a ring, a band movably carried by said ring, a series of teeth formed in the inner face of said band, a gear wheel engaging said teeth, 75 means for rotating said gear wheel, a belt connected to said ring and adapted to encircle the body of a wearer, and a padded backing plate also attached to said ring.

10. A stage costume appliance, including a ring adapted to encircle the body of a wearer, a band movably carried by said ring, means for rotating said band with respect to said ring, a spring pressed dog carried by said ring and normally adapted to engage said band to lock the same with respect to said ring, and a control connected to said dog for effecting a release of the same.

11. A costume appliance, including a ring adapted to encircle the body of a wearer, a band movably carried by said ring, means for rotating said band with respect to said ring, a shield carried by said band, said shield comprising a body portion, panels 95 movably secured adjacent the inner edges of said body portion and costume attaching means secured to said shield.

12. A costume appliance including a ring adapted to encircle the body of a wearer, 100 guide elements secured to said ring, a band concentrically disposed with respect to said ring and in contact with said guide elements, means attached to said ring and engaging said band to move the latter positively with respect to said ring, garment supporting means carried by said band, a belt adapted to embrace the body of the wearer and supporting means extending between said belt and said ring.

13. A costume appliance including a ring 110 adapted to encircle the body of a wearer, a band movably carried by said ring, means for rotating said band with respect to said ring, a spring pressed dog carried by said ring and normally adapted to engage said band to lock the same with respect to said ring, a flexible element having one of its ends connected to said dog and a hand grip connected to the opposite end of said element.

HENRY SKREMKA.
